UNITED STATES PATENT OFFICE

126,392

DESIGN FOR A LIGHTING FIXTURE BASE PLATE

Herbert J. Graham, Philadelphia, Pa.

Application August 1, 1940, Serial No. 94,113

Term of patent 14 years

To all whom it may concern:

Be it known that I, Herbert J. Graham, a citizen of the United States and a resident of Philadelphia, county of Philadelphia, State of Pennsylvania, have invented a new, original, and ornamental Design for a Lighting Fixture Base Plate, of which the following is a specification, reference being had to the accompanying drawing, forming a part thereof, wherein:

Figure 1 is a perspective view of the lighting fixture base plate showing my new design;

Figure 2 is a side elevational view thereof; and
Figure 3 is a top plan view thereof.

I claim:

The ornamental design for a lighting fixture base plate, as shown.

HERBERT J. GRAHAM.
